TRAFFIC REGISTERING MECHANISM

Curtis D. Cutler, Delaware, Ohio, assignor to
 Automatic Traffic Counter Company, Inc., Co-
 lumbus, Ohio, a corporation of Ohio

Application November 12, 1936, Serial No. 110,504

7 Claims. (Cl. 200—86)

This invention pertains to counting or registering mechanism and is particularly directed to an improved vehicle actuated switch for use in connection with mechanism for registering the number of vehicles traveling in either direction over a specified highway.

Certain types of traffic registering devices now in use employ a light beam which is focused on a light sensitive cell. When the beam is interrupted and a shadow is thrown on the cell, a circuit is completed and a registering is made. These types of registering mechanisms are objectionable because shadows may be made by objects other than those intended and also one object may pass in the shadow of a second object, making the device render a false indication. These registers are also required to be supplied with 110 or 220 volt electric current which eliminates their use on rural roads or any other place where such a current supply is not available.

The primary object of the present invention resides in the provision of an improved vehicle actuated switch which can be employed to control the circuit of a registering device in such a manner as to overcome the above noted objections.

Another object of the invention is the provision of a treadle switch which may be arranged transversely of a highway to be actuated by vehicles passing thereover in order to complete a circuit for an electrically energized registering mechanism.

A still further object rests in providing a traffic registering mechanism with a control switch which may be applied to a highway and employed to actuate the registering mechanism upon the passage of vehicles over the highway, the switch being so constructed as to be capable of controlling a plurality of circuits so that the direction of travel of the vehicles as well as the number will be made manifest.

It is also an object to form a switch with a pair of spaced stationary contacts and a single movable contact, the latter being moved into engagement with one of the former upon the passage of a vehicle thereover. The contacts are to be elongated and the movable one made flexible so that the opposite ends may be simultaneously engaged by vehicles traveling in opposite directions, and moved into engagement with the respective stationary contacts.

With these and other objects in view, the invention resides in the novel features of construction, combination of elements and arrangement of parts as particularly pointed out in the

following description and the accompanying drawing in which:

Fig. 1 is a perspective view of a section of a roadway to which a traffic counting device provided with a switch constructed in accordance with the present invention has been applied;

Fig. 2 is a vertical sectional view through a housing in which is located a pair of accumulative counters and the actuating mechanism therefor;

Fig. 3 is a vertical transverse sectional view through the actuating mechanism for one of the counters, the plane of the section being shown by the line III—III of Fig. 2;

Fig. 4 is a vertical transverse sectional view through the vehicle actuated switch on the plane indicated by the line IV—IV of Fig. 1;

Fig. 5 is an enlarged sectional view of a portion of the switch means.

Referring more particularly to the drawing, 20 the numeral 1 indicates a highway to which the registering mechanism 2 comprising the present invention is applied. Arranged transversely of the highway is a vehicle actuated switch 3 comprising an inverted T-shaped strip 4 which is 25 formed of rubber. The top of the vertical portion 5 of the strip includes the movable contact 5a of the switch. This contact is, in this instance, formed of an inverted V-shaped strip of woven wire fabric vulcanized in place on the rubber 30 strip when the latter is being cured. The horizontal flanges 6 of the strip 4 are covered by metallic strips 7 and the switch is secured in position on the roadway by nails or spikes 8 passing through the strips 7 and the flanges 6. The 35 switch is particularly illustrated in Fig. 4 and the dotted lines show the switch in either of its circuit closing positions. It will readily be seen that the vertical portion 5 of the strip may be flexed in either direction depending upon the direction 40 of movement of the vehicle engaging the same. When the portion 5 is bent over sufficiently, the contact 5a will engage with one of the strips 7 providing for current flow through these elements.

45 Current conducting wires lead from the switch 3 to a housing 9 suitably supported at the side of the roadway. Mounted on the rear wall of the housing 9 adjacent the upper portion thereof is a pair of Veeder or other suitable accumulative 50 counting devices 10, each of which is provided with an operating shaft 11, to the outer end of which is secured an operating lever 12. Also carried by the rear wall of the housing in vertical registration with the outer ends of the levers 12 55

is a pair of solenoid members 13. The members 13 are of the usual construction and to include a field winding 14 in the center of which is located a tubular sleeve 15. A bar-like core 16 is 5 slidably positioned in the sleeve 15 with the lower end thereof in engagement with the lower wall of the solenoid casing. The upper end of the core 16 is spaced from the lever 12 to permit the former to gain some momentum before engaging the latter. This is essential in a device of this 10 character because it provides for quick operation of the counting mechanism.

To correctly register the passage of a vehicle 15 moving at the rate of 60 M. P. H. over the road switch, the counting mechanism would have to be actuated twice, once for the front wheels and once for the rear wheels. To do this, the operating lever as well as the movable core must return to a normal position before each actuation 20 which requires the device to be capable of at least eighteen operations a second. If the core 16 and the lever 12 were connected by means of levers or other devices, such speed of operation would not be attainable.

25 The terminals of the windings 14 are connected with a pair of binding posts 17 provided on the casing of each of the solenoids. An electric battery 19 is provided in the lower part of the housing 9 and a wire 20 leading from one binding post of one solenoid to one binding post of the second solenoid is connected with one pole 21 of the battery. The other pole 22 of the battery 19 is connected by means of a conductor 23 with the movable contact 5a of the road 30 switch. The stationary contacts 7 of the road switch are connected by means of a second and third conductor 24 and 25 with the second binding posts 17 of the solenoids, the conductor 24 connecting one contact 7 with one solenoid and the conductor 25 leading from the other contact 40 7 to the other solenoid.

45 The device operates as follows: A vehicle passes over the road switch 3 and in doing so, the wheels move the vertical flange of the rubber strip to a substantially horizontal position as shown by dotted lines in Fig. 4 causing the contact 5a to engage one of the contact strips 7. Current will then flow from the battery 19 over the conductor 23 to the contact 5a, then to the strip 7 engaged by the contact 5a and over one of the conductors 50 24 or 25 to the field of the respective solenoid and then back to the battery by way of the wire 20.

55 This passage of current through the solenoid field causes the core to move upwardly and in doing so, engage the end of the lever 12 of the counter positioned above the solenoid. Continued movement of the core results in the movement of the lever to actuate the counter. Immediately 60 upon the separation of the contacts 5a and 7, current flow stops and the core 16 returns to its original position. This cycle of operation is completed twice for every vehicle which passes over the road switch. The total reading of the counter 65 is divided by two to give the actual number of vehicles passing over the road.

In the event two vehicles traveling in opposite directions pass over the switch at the same

time, the vertical portion of the strip 4 is sufficiently flexible to permit one end portion to engage with one strip 7 while the other end portion is in engagement with the other strip.

While I have shown and described my invention in its preferred form, it will be understood that many minor changes may be made therein without departing from the spirit and scope of the invention as defined by the following claims.

What is claimed is:

1. In a traffic registering mechanism, a vehicle actuated switch comprising an inverted T-shaped rubber strip, spaced stationary metallic strips carried by the base portion of said T-shaped strip, and a movable contact strip secured 15 to the vertical portion of said T-shaped strip adjacent the upper end thereof.

2. In traffic registering mechanism, a vehicle actuated switch comprising an elongated resilient strip, a vertically extending resilient web 20 formed at the longitudinal center of said strip, a metallic contact element secured to said strip on either side of said web, and a similar contact element secured adjacent the upper end of said web.

25 3. In traffic registering mechanism, a vehicle actuated switch comprising an elongated strip, a resilient vertical web formed with said strip at its longitudinal center, said web being coextensive with said strip, a metallic contact element 30 secured to the upper surface of said strip on either side of said web, and a similar contact element secured adjacent the upper end of said web.

4. In traffic registering mechanism, a vehicle actuated switch comprising a substantially flat 35 elongated rubber body, a vertical web coextensive with said body and joined thereto at the longitudinal center thereof, contact elements coextensive with said body and secured thereto on either side of said web, and a metallic fabric element 40 extending around the upper free edge of said web and joined therewith during the formation of said body.

5. A vehicle actuated switch comprising an elongated flexible body, a pair of stationary elongated contacts carried by said body in spaced relation to one another, and a flexible contact carried by said body between said spaced contacts, the opposite ends of said flexible contact being capable of simultaneous movement into 45 engagement with opposite stationary contacts.

6. A vehicle actuated switch comprising an elongated resilient strip, a vertically extending resilient web formed at the longitudinal center of said strip, a stationary metallic contact element 55 secured to said strip on either side of said web, and a movable contact element carried by said web in spaced relation to said stationary contacts.

7. A vehicle actuated switch comprising an elongated resilient strip, a resilient web formed 60 with and extending from said strip at an angle thereto, a stationary elongated metallic contact element secured to said strip, and a movable contact element carried by said web in spaced relation to said first contact, said contacts 65 engaging one another upon movement of said web.
